United States Patent Office

Des. 187,412
Patented Mar. 8, 1960

187,412

HANDLE FOR FAUCETS OR THE LIKE

Stephen A. Young, Delphi, Ind.

Application January 13, 1958, Serial No. 49,217

Term of patent 14 years

(Cl. D91—3)

Fig. 1

Fig. 2

Fig. 3

Fig. 4

Figure 1 is a top plan view of the handle for faucets or the like embodying my new design.

Figure 2 is a side elevation thereof.

Figure 3 is a bottom plan view thereof.

Figure 4 is a sectional view taken about on the line 4—4 of Figure 1.

I claim:

The ornamental design for a handle for faucets or the like, substantially as shown.
